GELATIN BLASTING EXPLOSIVE
COMPOSITION

James Taylor, Ardrossan, Arthur J. Lowe, West Kilbride, and Edward G. Cooke, Ardrossan, Scotland, assignors to Imperial Chemical Industries Limited, a corporation of Great Britain

No Drawing. Application June 7, 1950,

Claims priority, application Great Britain
July 29, 1949

11 Claims. (Cl. 52—7)

1

The present invention relates to new and improved gelatine blasting explosives. It is well known that the tendency is for the velocity of detonation and sensitivity characteristics of cartridges of gelatine explosive to diminish as the pressure under which they are used is increased.

The main object of the invention is to provide gelatine blasting explosives of improved serviceability under conditions of hydrostatic pressure substantially exceeding 10 atmospheres such as may be encountered in submarine blasting or in seismic blasting operations.

A gelatine blasting explosive according to the present invention consists of a liquid explosive nitric ester-nitrocellulose gelatine composition containing at least 35% by weight of a mixture of nitrocellulose and a liquid nitric ester liquid composition based on the weight of said nitric ester-nitrocellulose gelatine composition and 2½% to 27½% by weight of a water insoluble finely divided barium salt of a polybasic acid, the said liquid composition being thickened by the nitrocellulose and containing at least a major quantity of liquid nitric ester.

The said liquid composition may include a liquid nitrobody as for example a mono-nitro-toluol as for instance ortho-nitrotoluol.

The water insoluble barium salt of a polybasic acid is employed in a state of fine division passing a 300 E. S. S. screen and preferably in the form of an impalpable powder such as is used in pigments for paints and enamels, whether produced by chemical precipitation or by milling the naturally occurring mineral. There may be used for instance precipitated barium sulphate, or milled barytes, precipitated barium carbonate, or witherite, or precipitated barium chromate, or barium phosphate.

The improved gelatine explosives may for instance approximate in their compositions to conventional blasting gelatine, sodium nitrate gelignites or ammonium nitrate gelignites. Thus a blasting gelatine-like explosive having very much improved retention of its high velocity of detonation under conditions of increasing hydrostatic pressures may be obtained by incorporating the finely divided water insoluble barium salt of a polybasic acid into ordinary blasting gelatine, preferably during the mixing operation in which the nitroglycerine-nitrocellulose paste is brought into the form of a jelly by effecting complete solution of the nitrocellulose in the liquid explosive nitric ester. In the case of a sodium gelignite-like explosive the finely divided barium salt is preferably incorporated along with the sodium nitrate or the vegetable tissue ingredients or both

5 into the nitrocellulose-liquid explosive nitric ester paste. In these explosives the proportion of liquid nitric ester-nitrocellulose jelly will usually be at least 50% in order to maintain the power of the explosive. Ammonium nitrate gelignite-like explosives may be prepared in an analogous manner to that employed in the production of the sodium nitrate gelignite-like explosives. The ammonium nitrate being an explosive salt as well as an oxidising agent, the amount of the liquid explosive nitric ester-nitrocellulose jelly may in general be nearer to the lower limit of 35% hereinbefore indicated. As will be understood, however, intermediate types of explosives between these three classes, 10 and other types falling within the definition of the invention but not corresponding closely to the character of blasting gelatine, sodium nitrate or ammonium nitrate gelignites, may also be made. The explosives provided according to the present 15 invention are characterised by the fact that they retain to a remarkable degree the normal velocity of detonation which they exhibit under atmospheric pressure, even when they are subjected to hydrostatic pressures of 20, 30, 40 or even beyond 20 40 atmospheres; and many of them also maintain their sensitiveness to detonation by the agency of the aluminium encased blasting detonators of 25 customary commercial power unimpaired under these conditions. Moreover their propagating characteristics from cartridge to cartridge as determined by the gap test remain in all cases satisfactory.

30 Apart from their use in submarine blasting and seismic blasting operations, the improved gelatine blasting explosives may also be employed for other purposes where high velocity of detonation is desired, for example in plaster shooting, or blasting in hard rock, even at ground level.

The invention is illustrated by the following examples in which the parts are parts by weight 35 except where otherwise indicated.

Example 1

	Per cent
80:20 mixture of nitroglycerine and ethyl-	
45 ene glycol dinitrate	57.5
“Blasting soluble” nitrocellulose	2.4
Woodmeal	10.0
Sodium nitrate	24.8
Finely milled barytes as used as a pigment	
in paints	5.0
Chalk	0.3

50 The liquid explosive nitric ester mixture, the nitrocellulose and a portion of the woodmeal are first mixed by hand and the remaining ingredi-

3

ents are introduced one by one into the resulting pasty mass in a McRoberts mixer in the order given, the running of the mixer being continued until the nitrocellulose is completely gelatinised and the other ingredients are well distributed through the resulting jelly. The resulting sodium nitrate gelignite-like explosive is cartridge by extrusion into rigid interconnectable waxed paper containers as used for seismic prospecting.

When a file of cartridges of 5 cm. diameter separated by 1 cm. gaps between their ends is exposed at 40 atmospheres pressure of water for 24 hours it is found that the first cartridge is satisfactorily initiated by a No. 8 aluminium encased lead azide-tetryl detonator and that the 15 third cartridge in the file of cartridges detonates at a velocity of 7500 metres per second.

In a comparative test of an explosive of similar consistency not in accordance with the invention and in which for the barytes there is substituted a further 5.0% of sodium nitrate, the velocity of detonation of the file of cartridges is 1700 at a water pressure of 3.3 atmospheres. At 5 atmospheres the second cartridge fails to detonate.

Example 2

Per cent

80:20 mixture of nitroglycerine and ethylene glycol dinitrate	87.0
Blasting soluble nitrocellulose	7.4
Finely milled barytes as specified in Example 1	5.0
Chalk	0.6

The liquid explosive nitric ester and the nitrocellulose are first mixed by hand and the barytes and chalk are then introduced into the resulting pasty mass in a McRoberts mixer the running of which is continued until the nitrocellulose is completely gelatinised and the barytes and chalk are well distributed through the jelly. The resulting blasting gelatine-like explosive composition is cartridge by extrusion into rigid containers made of waxed paper. When a file of cartridges of 5 cm. diameter separated by 1 cm. gaps is exposed to a water pressure of 37 atmospheres for half an hour it is found that the first cartridge is satisfactorily initiated by a No. 8 aluminium encased lead azide-tetryl detonator and that the third in the file of cartridges detonates at a velocity of 7900 metres per second.

With a comparative blasting gelatine explosive not in accordance with the invention and consisting of 91.2% of the aforesaid 80:20 mixture of explosive liquid esters, 8.2% of the "blasting soluble" nitrocellulose and 0.6% chalk and containing no barytes tested in similar containers similarly spaced with similar detonators the third in the file of cartridges detonates with a velocity less than 1500 metres per second under a hydraulic pressure of 20 atmospheres and the velocity of detonation is still under 1500 metres per second when the hydraulic pressure is as low as 7 atmospheres, whereas the velocity of detonation is 7800 metres per second at atmospheric pressure.

The explosive of Example 2 is suitable for submarine blasting and seismic blasting at hydraulic pressures up to about 40 atmospheres and also for normal pressure blasting operations calling for high velocities of detonation.

Example 3

Per cent

80:20 mixture of nitroglycerine and ethylene glycol dinitrate	58.1
Chalk	75

4

"Blasting soluble" nitrocellulose	3.2
Woodmeal	7.6
Sodium nitrate	25.8
Milled barytes as used in Example 1	5.0
Chalk	0.3

The explosive is made and cartridge as described in Example 1. When a file of cartridges of 5 cm. diameter separated by 1 cm. gaps is exposed at 40 atmospheres water pressure for half an hour and initiated with a detonator similar to that used in the tests described in the previous examples the third in the file of cartridges detonates at a velocity of 6530 metres per second.

In a comparative test of an explosive of similar consistency not in accordance with the invention and in which for the barytes there is substituted a further 5.0% of sodium nitrate, the velocity of detonation of the file of cartridges is 1710 at a water pressure of 3.3 atmospheres. At 5 atmospheres the second cartridge in the file fails to detonate.

Example 4

25 The composition is the same as in Example 1 except that precipitated barium sulphate is used instead of milled barytes. The explosive is similarly made and cartridge.

When a similarly arranged file of the cartridges after exposure for 4 hours to a water pressure of 20 atmospheres is similarly initiated the third in the file of cartridges detonates at a velocity of 7900 metres per second.

Example 5

Per cent

80:20 mixture of nitroglycerine and ethylene glycol dinitrate	35.0
"Blasting soluble" nitrocellulose	1.4
Woodmeal	4.0
Milled barytes as used in Example 1	5.0
Ammonium nitrate	54.0
Chalk	0.3
Diammonium hydrogen phosphate	0.3

45 The manner of making and cartridge the explosive composition is similar to that described in Example 1.

When a similarly arranged file of the cartridges after exposure for 5 hours at a water pressure of 40 atmospheres is similarly initiated the third in the file of cartridges detonates at a velocity of 6520 metres per second. This barytes modified ammonium nitrate gelignite, unlike conventional ammonium nitrate gelignites, can thus be used for seismic shooting at pressures of the order of 40 atmospheres.

Example 6

Per cent

60 80:20 mixture of nitroglycerine and ethylene glycol dinitrate	46.0
"Blasting soluble" nitrocellulose	4.0
Ortho-nitrotoluol	4.0
Milled barytes as used in Example 1	5.0
65 Ammonium nitrate	40.7
Chalk	0.3

The explosive is mixed and cartridge in a fashion similar to that of the preceding examples. When a file of cartridges similarly arranged and initiated is subjected to a water pressure of 60 atmospheres for 5 hours the third in the file of cartridges detonates at a velocity of 7150 metres per second. The explosive is suitable for use in seismic blasting.

5

Example 7

	Per cent
80:20 mixture of nitroglycerine and ethylene glycol dinitrate	50.0
"Blasting soluble" nitrocellulose	2.0
Woodmeal	10.0
Precipitated barium chromate as used as a pigment in enamels	5.0
Sodium nitrate	32.4
Chalk	0.3
Di-ammonium hydrogen phosphate	0.3

The explosive composition is made and cartridge in a fashion similar to that described in Example 1. When a file of cartridges similarly arranged and initiated is subjected to a water pressure of 27 atmospheres for 5 hours the third in the file of cartridges detonates at a velocity of 7140 metres per second. This barium chromate modified sodium nitrate is suitable for seismic blasting purposes and submarine blasting purposes.

Example 8

The composition is the same as in Example 7 except that finely powdered precipitated barium carbonate is used instead of the barium chromate. The manner in which the explosive is made is otherwise the same as in Example 7 and it is similarly cartridge. When a file of cartridges arranged and initiated in a similar manner is exposed to a water pressure of 27 atmospheres for 5 hours the third in the file of cartridges detonates at a velocity of 6520 metres per second.

Example 9

The composition is the same as in Example 7 except that barium phosphate is used instead of barium chromate. The explosive is similarly made and cartridge.

When a similarly arranged file of the cartridges after exposure for 3 hours to a water pressure of 54 atmospheres is similarly initiated the third in the file of cartridges detonates at a velocity of 7150 metres per second.

Example 10

5 parts of milled barytes as used in Example 1 are worked in a McRoberts mixer into 95 parts of a military gelatine explosive intended to withstand rifle bullet fire without detonating and containing

	Per cent
Nitroglycerine	68.3
"Blasting soluble" nitrocellulose	5.7
Guncotton	10.0
Mono-nitrotoluol	14.6
Diethyl diphenyl urea	0.9
Chalk	0.3

The explosive is cartridge in the same way as in the preceding examples. When a file of the cartridges arranged and initiated by a similar detonator is exposed at a water pressure of 100 atmospheres for 5 hours the third in the file of cartridges detonates at a velocity of 7500 metres per second.

A similar cartridge of the aforesaid military gelatine explosive composition not in accordance with the invention, due to the absence of barium salt, fails to detonate even at atmospheric pressure when an attempt is made to initiate it with a similar detonator even at atmospheric pressure in the absence of an intermediate primer. When such a primer is used the third in a file of such cartridges detonates at a velocity of 7000 metres per second at atmospheric pressure.

6

Example 11

	Per cent
80:20 mixture of nitroglycerine and ethylene glycol dinitrate	57.5
"Blasting soluble" nitrocellulose	2.4
Woodmeal	5
De-proteinised de-oiled peanut meal passing 16 and retained by 100 mesh B. S. S. screen	5
Finely milled barytes as specified in Example 1	3
Sodium nitrate	26.4
Di-ammonium hydrogen phosphate	0.3
Chalk	0.3

15 The ingredients are mixed and the cartridges are prepared and tested as described in Example 1. On exposure at 27 atmospheres water pressure for 24 hours the third cartridge in the file detonates at a velocity of 6800 metres per second.

Example 12

	Per cent
80:20 mixture of nitroglycerine and ethylene glycol dinitrate	50
"Blasting soluble" nitrocellulose	2.4
De-proteinised de-oiled peanut meal passing 16 and retained by 100 mesh B. S. S. screen	9
Finely milled barytes as used in Example 1	5
Sodium nitrate	33.3
Chalk	0.3

35 The composition is mixed and the cartridges are prepared and tested as described in the preceding example except that the time of exposure and the water pressures are different. On exposure for 5 hours to a water pressure of 60 atmospheres the third cartridge in a file detonates at a velocity of 6800 metres per second. On exposing another file for five hours to a water pressure of 106 atmospheres the third cartridge in the file still detonates satisfactorily. At such high pressures however occasional failures occur owing to the detonators being liable to collapse.

40 The de-proteinised de-oiled peanut meal which is used in Examples 11 and 12 is the dried substantially de-proteinised material obtained by aqueous alkaline extraction, washing and de-watering of peanuts from which the oil has been removed successively by expression and by extraction with a volatile oil solvent. The screened material has a bulk density of approximately 0.46 gm. per c. c. under a packing pressure of 25 lb./sq. in. and approximately 0.51 gm. per c. c. under a packing pressure of 75 lb./sq. in. It contains approximately 44% carbon, 4.5% nitrogen and 6% hydrogen.

Example 13

	Per cent
80:20 mixture of nitroglycerine and ethylene glycol dinitrate	50
"Blasting soluble" nitrocellulose	1.8
Oat husk meal	9
Barytes as used in Example 1	5
Balsa woodmeal	3.2
Sodium nitrate	30.7
Chalk	0.3

75 The composition is mixed and the cartridges are made up and tested as in the preceding examples, except that the gaps between the cartridges are increased to 2.5 cm. and a No. 6 detonator is used instead of a No. 8. When exposed for 24 hours to a water pressure of 66 atmospheres the velocity of detonation of the third cartridge in the file is 6250 metres per second.

Example 14

Per cent

80:20 mixture of nitroglycerine and ethylene glycol dinitrate	45
"Blasting soluble" nitrocellulose	3.5
Barytes as used in Example 1	5
Ammonium nitrate	45.9
Chalk	0.3
Di-ammonium hydrogen phosphate	0.3

The ingredients are mixed and the cartridges are made up and tested as in Example 12 except that the gaps between the cartridges are again reduced to 1 cm. When subjected for 24 hours to a water pressure of 40 atmospheres the velocity of detonation is 6820 metres per second. In a test where the water pressure is increased to 66 atmospheres the cartridge detonates satisfactorily.

Example 15

Per cent

80:20 mixture of nitroglycerine and ethylene glycol dinitrate	35
"Blasting soluble" nitrocellulose	2.3
Mono-nitrotoluol	1.9
Woodmeal	0.3
Ammonium nitrate	42.9
Di-ammonium hydrogen phosphate	0.5
Chalk	0.3
Barytes as used in Example 1	16.8

The composition is mixed and the cartridges are made up and tested with a No. 6 detonator as in Example 13 except that the gaps between the cartridges are 0.5 cm. When subjected for 24 hours to a water pressure of 50 atmospheres the velocity of detonation is 6500 metres per second.

Example 16

Per cent

80:20 mixture of nitroglycerine and ethylene glycol dinitrate	31.5
"Blasting soluble" nitrocellulose	2.1
Mono-nitrotoluol	1.7
Woodmeal	0.2
Ammonium nitrate	38.5
Di-ammonium hydrogen phosphate	0.5
Chalk	0.3
Barytes as used in Example 1	25.2

The composition is mixed and the cartridges are made up and tested as in Example 14. When subjected for 24 hours to a water pressure of 50 atmospheres the velocity of detonation is 6250 metres per second.

In the preceding examples the term "blasting soluble" nitrocellulose means the product of nitration of purified cotton cops by the pot process to a nitrogen content of 11.95 to 12.25%. The product is at least 95% soluble in an ether-alcohol solution and has a viscosity of 100 to 300 c. g. s. in solution of 3 gms. in 100 ml. acetone (95%) at 20°C.

What we claim is:

1. A gelatine blasting explosive containing

2 1/2% to 27 1/2% by weight of a water insoluble finely divided barium salt of a polybasic acid, and at least 35% by weight of a liquid composition consisting of at least a major quantity of liquid nitric ester thickened by a minor quantity of nitrocellulose.

2. A gelatine blasting explosive containing 2 1/2% to 27 1/2% by weight of a water insoluble finely divided barium salt of a polybasic acid, at least 35% by weight of a liquid composition consisting of at least a major quantity of liquid nitric ester thickened by a minor quantity of nitrocellulose, and a liquid nitrobody.

3. A gelatine blasting explosive as claimed in claim 2 wherein the liquid nitrobody is a mono-nitrotoluol.

4. A gelatine blasting explosive as claimed in claim 2 wherein the liquid nitrobody is ortho-nitrotoluol.

5. A gelatine blasting explosive as claimed in claim 1 wherein the water insoluble barium salt of a polybasic acid is barium sulphate.

6. A gelatine blasting explosive as claimed in claim 1 wherein the water insoluble barium sulphate of a polybasic acid is milled barytes.

7. A gelatine blasting explosive as claimed in claim 1 wherein the water insoluble barium salt of a polybasic acid is precipitated barium carbonate.

8. A gelatine blasting explosive as claimed in claim 1 wherein the water insoluble salt of a polybasic acid is milled witherite.

9. A gelatine blasting explosive as claimed in claim 1 wherein the water insoluble barium salt of a polybasic acid is precipitated barium chromate.

10. A gelatine blasting explosive as claimed in claim 1 wherein the water insoluble barium salt of a polybasic acid is barium phosphate.

11. A cartridge containing the gelatine blasting explosive claimed in claim 1.
